PAPER STOCK FLOW SYSTEM

George W. Sargent, Beloit, Wis., assignor to Beloit Iron Works, Beloit, Wis., a corporation of Wisconsin
Filed Oct. 2, 1961, Ser. No. 142,126
5 Claims. (Cl. 137—563)

The present invention relates to a paper stock flow circuit for a paper making machine and to an improved flow selector valve for selecting a supply flow from a plurality of moving fluid suspensions such as different stock supply sources in a paper mill.

The invention is advantageously embodied in a system containing fluids with material in suspension with the fluids kept moving so that the particles do not congest or settle out. In certain fields of use a selector valve is provided for selecting a flow for delivery and use from one of a plurality of sources of fluid suspensions. Such uses may be found in the food, oil and chemical industries and a particularly important use is found in a paper mill where different paper stocks are selectively delivered to a forming machine such as to the head box to be flowed onto a moving Fourdrinier wire. While it will be understood that the features of the invention are useful in many environments, for convenience of disclosure and because of the advantages particularly afforded in a paper making machine, the features of the invention will be disclosed and described in connection with a paper machine.

In devices heretofore used, difficulties were encountered from plugging of the connections between the supply lines and the selector valve. While the fluid suspension, such as the paper stock, is kept moving in the supply lines, dead areas of nonmovement exist between the supply line which is not used and the selector valve or between both supply lines and the selector valve if no stock is being drawn. The concentration and settling of stock provides a plug which creates a hazard when the valve is opened for normal use. The plug will obstruct the free flow of stock from the main supply line to the take off line, or break loose and cause trouble in the downstream system.

It is accordingly an object of the present invention to provide an improved system which eliminates the formations of plugs in the so-called dead area between the selector valve and the main supply line in a circulating system for a fluid suspension.

It is a further object of the invention to provide an improved selector valve which is capable of delivering a fluid suspension to a take off line from one of a plurality of supply circuits without creating dead areas and settled material in the circuit not being used.

A further object of the invention is to eliminate the necessity of providing dual valves in a system for selecting paper supply stock from separate moving circulating systems.

It is a still further object of the invention to provide an improved selector valve for a system of the above-described type, which is simple and compact in construction and which requires a minimum of maintenance.

Other objects, advantages and features will become more apparent with the teaching of the principles of the invention in connection with the disclosure of the preferred embodiments thereof in the specification, claims and drawings in which:

FIGURE 1 is a schematic showing of a portion of a stock supply system in a paper mill;

FIGURE 2 is a top plan view of a selector valve embodying the principles of the present invention;

FIGURE 3 is a vertical sectional view taken substantially along line III—III of FIGURE 2;

FIGURE 4 is a fragmentary elevational view showing a mechanism for adjusting the selector valve; and

2

FIGURE 5 is a fragmentary perspective view showing a portion of the interior of one of the supply circuits.

As shown on the drawings:

FIGURE 1 illustrates a portion of a paper stock supply system wherein a selector valve 10 is provided to select stock from continuous flow supply systems 11 and 12. The stock is provided from a digester to a collecting tank 13, in each of the systems. The suspension of paper stock fibers in water flows through the circuits in the direction shown by the arrows past the selector valve 10 and continual circulation is maintained by pumps 14.

For operation, the selector valve 10 is set to connect a take off line 15 to either of the systems and the stock flows to a stuff box 16 and then to the head box and of course it may first pass through a screen and be distributed to the head box through a header whereupon it flows upon a foraminous forming surface such as a Fourdrinier wire.

The different systems 11 and 12 will be provided with different grades of stock, and the selector valve 10 will be set for either grade of stock depending upon the paper that is to be made. Provisions normally must be made to drain the unused stock from the take off line when switching to another stock, and in the form of the valve shown in FIGURES 2 and 3 this function is obtained as will be described.

In the selector valve assembly of FIGURES 2 through 5, a valve housing is provided including a pair of parallel cylindrical pipes or tubes 17 and 18 which are tangentially positioned with respect to a central housing portion 19. The pipes are shown as cast integral with the central housing portion 19 and are flanged at their ends and drilled to be connectible into the flow conduit systems 11 and 12 as shown in FIGURE 1.

The central housing portion 19 is hollow and forms a circular slightly tapered chamber 20 therein with a circular slightly tapered valve plug 21 in the chamber. Inlet ports 22 and 23 are formed at the sides of the chamber 20 where it is tangential to the pipes 17 and 18.

The valve plug 21 has a flow passage 24 therethrough with ends at 25 and 26. The end 26 is in constant communication with the take off line 15, and the end 25 selectively communicates, with rotation of the valve plug, with the inlet port 22 or the inlet port 23.

The chamber 20 in the housing is closed over the end of the valve plug 21 by a plate 27 provided with a gasket at the edge and held to the housing by cap screws 28. A flow outlet opening at 29 is provided through the center of the plate for discharge to the take off line 15, and circumferentially arranged threaded holes 27a are provided in the plate for the connection of a fitting leading to the take off line. A sealing ring 29a is positioned around the outside of the opening at the axial end of the valve plug.

The other end of the chamber 20 is closed by a plate 30 held to the housing by cap screws 31 and having a gasket at the edge. The valve plug 21 is provided with a boss or stub shaft 32 for rotation of the valve, and the shaft projects through an opening in the plate 30 and is sealed by a packing gland 33.

The inlet ports 22 and 23 are substantially 180° apart and between them are drain ports 34 and 35 formed through the sides of the cylindrical portion 19 of the housing. These drain ports communicate with drain lines 36 and 37 for draining stock from the take off line 15 when the valve plug is rotated to change its setting from one supply circuit to the other. The valve housing of FIGURES 2 and 3 is arranged to deliver to an overhead take off line. If stock is pumped from the supply circuit 12, and the selector valve 10 is changed to pump stock from the circuit 11, the valve plug 21 is rotated through 90° so that the opening 25 communicates with either drain port 34 or

35. The head of stock in the take off line will then drain out through a drain line and be clear when the plug is rotated the remaining 90° to communicate with the inlet port 23. If the stock is to be saved, one drain line can be designated for drain from one supply circuit and the other drain line for drain from the other supply circuit. 5

It is to be particularly noted that, as shown in FIGURES 3 and 5, the valve plug 21 has its outer peripheral wall or surface 21a which blocks the inlet port not being used at its point of entry from the tubular pipe. Thus 10 no dead spots remain to form a plug of stock, and flow will be continuous in the circuit of the pipe that is blocked. The circular wall 21a operates the same from each inlet port, or for both inlet ports when the valve plug 21 is turned to the drain position. 15

FIGURE 4 illustrates mechanism for setting the selector valve, and a gear 38 is keyed to the shaft 32 and driven by a worm 40 on a shaft 40a rotatably mounted on brackets 39 on the housing. A hand wheel 41 is secured to the shaft 40a for turning the worm. 20

In summary, stock continually circulates through the conduits or circuits 11 and 12, and the selector valve 10 is rotatable to select flow from either circuit for the take off line 15. As shown in FIGURES 3 and 5, when the flow passage 24 through the valve plug 21 communicates 25 with one inlet, the circular outer surface 21a of the valve plug blocks the other inlet port at the surface of the wall of the pipe of the circuit not being used so that no dead spot or recess remains. Stock is delivered out through the outlet port 29 to the lines leading to the 30 forming section of the paper machine.

Thus it will be seen that I have provided an improved flow system embodying a flow selector valve which meets the objectives and advantages above set forth. The unit provides a compact self-cleaning valve avoiding the disadvantages present in systems heretofore used. While in a preferred arrangement the valve as shown is delivering stock overhead, it will be appreciated that by changing the passage through the valve plug to a horizontal 40 passage, and either omitting or changing the position of the drain lines, a horizontal discharge could be obtained. 40

The drawings and specification present a detailed disclosure of the preferred embodiments of the invention, and it is to be understood that the invention is not limited to the specific forms disclosed, but covers all modifications, changes and alternative constructions and methods falling within the scope of the principles taught by the invention. 45

I claim as my invention:

1. A paper stock flow system comprising, 50
a take off line for leading to a head box,
a first paper stock circulating supply line,
a second paper stock circulating supply line,
a selector valve connected between said lines having
spaced first and second passages connected to said
first and second lines,

an outlet passage leading from the valve to the take 60
off line with said outlet passage and take off line
leading upwardly above the valve,

first and second drain lines leading from the valve,
a rotatable valve plug having a passage communicating
with the outlet passage in all operative positions
and selectively communicating with one of said first
and second supply lines and said first and second 65
drain lines.

so that stock is supplied to the take off line from either
supply line or said take off line is drained into said
first or second drain lines. 70

2. A paper stock flow system comprising, 70
a take off line for leading to a head box,
a first paper stock circulating supply line,
a second paper stock circulating supply line,
a selector valve connected between said lines having
spaced first and second passages connected to said
first and second lines, 75

spaced first and second passages connected to said
first and second lines,
an outlet passage leading from the valve to the take
off line with said outlet passage and take off line
leading upwardly above the valve,
a drain line leading from the valve,
a rotatable valve plug having a passage communicating
with the outlet passage in all operative positions
and selectively communicating with one of said first
and second supply lines and said drain line,
so that stock is supplied to the take off line from either
supply line or said take off line is drained into said
drain line.

3. A paper stock flow system comprising,
a take off line for leading to a head box,
a first paper stock circulating supply line,
a second paper stock circulating supply line,
a selector valve connected between said lines having
spaced first and second passages connected to said
first and second lines,

said stock supply lines having continuous inner
walls with said first and second valve passages
opening from said walls,
an outlet passage leading from the valve to the take
off line with said outlet passage and take off line
leading upwardly above the valve,
a drain line leading from the valve,
a rotatable valve plug having a passage communicating
with the outlet passage in all operative positions
and selectively communicating with one of said first and
second supply lines and said drain line,
so that stock is supplied to the take off line from either
supply line or said take off line is drained into said
drain line,

said valve plug having a peripheral surface positioned
to form a continuation of said inner walls so that stock
will be prevented from collecting in the passages when the plug closes said
passages.

4. A paper stock flow system comprising,
a take off line for leading to a head box,
a first paper stock circulating supply line,
a selector valve connected between said lines having
spaced first and second passages connected to said
first and second lines,

said first and second passages being parallel to
each other,
said stock supply lines having continuous inner
walls with said first and second valve pas-
sages opening from said walls,

an outlet passage leading from the valve to the take
off line with said outlet passage and take off line
leading upwardly above the valve,
a drain line leading from the valve,
a rotatable valve plug having a passage communicating
with the outlet passage in all operative positions
and selectively communicating with one of said first
and second supply lines and said drain line,

so that stock is supplied to the take off line from either
supply line or said take off line is drained into said
drain line,

said valve plug having a peripheral surface positioned
to form a continuation of said inner walls so that stock
will be prevented from collecting in the passages when the plug closes said
passages.

5. A paper stock flow system comprising,
a take off line for leading to a head box,
a first paper stock circulating supply line,
a selector valve connected between said lines having
spaced first and second passages connected to said
first and second lines,

said stock supply lines having continuous inner
walls with said first and second valve passages
opening from said walls,
an outlet passage leading from the valve to the take

off line with said outlet passage and take off line leading upwardly above the valve,
a drain line leading from the valve,
a rotatable valve plug having a passage communicating
with the outlet passage in all operative positions and
selectively communicating with one of said first and
second supply lines and said drain line,
said valve plug having a peripheral surface positioned
to project into said passages a slight
distance to form a substantial continuation of
said inner walls with the absence of non-flow
areas so that stock will be prevented from col-

lecting in the passages when the plug closes said
passages,
said valve plug passage being smooth surfaced
and turning at an angle through the plug.
